DESIGN FOR A PULLEY BLOCK

Henry Auslander, Brooklyn, N. Y.

Application March 19, 1942, Serial No. 106,251

Term of patent 14 years

To all whom it may concern:

Be it known that I, Henry Auslander, a citizen of the United States and resident of Brooklyn, New York, in the county of Kings and State of New York, have invented a new, original, and ornamental Design for a Pulley Block, of which the following is a specification, reference being had to the accompanying drawing, forming a part thereof.

In the drawing:

Fig. 1 is a front elevational view of a pulley block, showing my new design.

Fig. 2 is a side elevational view of the same.

Fig. 3 is a top plan view of the same.

Fig. 4 is a bottom plan view of the same.

I claim:

The ornamental design for a pulley block, as shown.

HENRY AUSLANDER.
